UNITED STATES PATENT OFFICE.

PHIL H. KNOWLTON AND LOUIS WILLIAMS, OF DENVER, COLORADO.

LOCKING CLOTHES-RACK.

No. 863,726.

Specification of Letters Patent.

Patented Aug. 20, 1907.

Application filed February 18, 1907. Serial No. 358,131.

To all whom it may concern:

Be it known that we, PHIL H. KNOWLTON and LOUIS WILLIAMS, citizens of the United States of America, residing at Denver, in the county of Denver and State 5 of Colorado, have invented certain new and useful Improvements in Locking Clothes-Racks, of which the following is a specification.

Our invention relates to locking clothes-racks and has for its object to provide a device which combines 10 simplicity of construction with practicability in use and by which the suspended clothes, such as hats and coats, may be locked against removal by unauthorized persons.

We attain our object by the mechanism illustrated 15 in the accompanying drawings, in the various views of which like parts are similarly designated and in which,

Figure 1—represents a front elevation or face view of the device, Fig. 2—a rear elevation thereof, Fig. 20 3—a vertical section taken along a line 3—3, Fig. 2, Fig. 4—a rear elevation of the device with its operating parts in the open or unlocked position, Fig. 5—a vertical section taken along a line 5—5, Fig. 4, Fig. 6—a top view of the casing, Fig. 7—a cross section along 25 a line 7—7, Fig. 4, Fig. 8—a sectional fragmentary view of the casing showing the interior of the key sheath, Fig. 9—an edge view of the latter, Fig. 10—a cross section along the line 10—10, Fig. 9, and, Figs. 11—12—respectively—a face and edge view of the key- 30 member.

In the drawings, 5 represents a casing composed of a plate 6 and a surrounding flange 7 and adapted to be secured to a wall by means of screws 8. Casing 5 is provided with two centrally disposed, vertically 35 aligned, hook members 9 and 10 including curved, outwardly ranging arms 9^a and 10^a which terminate in, in practice, diametrically aligned, spherical knobs or heads 9^c and 10^c.

Hook 9 is fixedly secured upon the lower portion of 40 the casing by screws 11 or analogous fastening means while the arm 10^a of the opposite member 10 forms part of a slide 12 which, projecting through a centrally and vertically disposed slot 13 in the plate 6 and the upper portion of the flange 7, is arranged to move reciprocatingly in relation to the stationary member 9. Slide 12 has an integral, downwardly ranging extension or tail piece 12^a which, when the member is in 45 its uppermost position, covers the slot 13.

A bar 14 movably held within the casing in a suitably arranged seat 15 is secured at its upper extremity, to the slide 12 by means of screws 16, while its lower extremity 14^a being bent at right angles to the main body, is connected with the uppermost portion of the surrounding flange 7, of the casing, by means of a vertically extending, helically wound spring 17. The 55 bar 14 is provided with a rack 18, the teeth of which,

cut in one of its edges, are ratchet shaped, and furthermore, with an elongated notch 19 cut in the edge of the bar in adjacency to the upper extremity of the rack.

60

A bell crank lever 20 is fulcrumed within the casing at 21, its lower arm being normally in engagement with the rack 18 while its other, shorter, arm has a knife edged extremity, situated below the vertically arranged key sheath 22. The latter being detachable 65 upon the plate 6 of the casing, extends through a correspondingly shaped opening in the upper portion of the flange 7 and is provided in one of its sides, in proximity to its lower edge, with two or more rows of circular apertures 23 axially alined with correspondingly shaped recesses 24 in the inner surface of the opposite side.

70

Pins 25, placed in the holes and recesses of the sheath, are designed to interrupt progress of any instrument other than the appropriately fashioned key, inserted in 75 the sheath for the purpose of actuating the operating mechanism.

75

The permutation lock thus obtained may, by interchanging of the pins, be made suitable to any one of a number of differently shaped keys, such as illustrated 80 in Figs. 11 and 12, composed of a flat shank 26, having an integral head 26^a and provided at its lower edge with one or more, longitudinally extending slots 26^b, which permit the key member to straddle one or more of the transverse pins 25 in the sheath.

85

A recess 26^d in one of the longitudinal edges of the key, is arranged to register with a correspondingly shaped opening 27 in the inner edge of the sheath, when the operating mechanism of the device is in the open or unlocked position, as shown in Fig. 4.

90

A lever 28, whose extremities 28^a and 28^c, extend in opposite directions at an angle to the main body, is fulcrumed upon plate 6 of the casing, intermediate the sheath 22 and the reciprocating bar 14.

95

When the movable parts of the device are in the open state, and the bar 14 is consequently in its uppermost position, with the extension 14^a in engagement with the lower surface of the seat 15, the extremities 28^a and 28^c of the lever 28 occupy, respectively, the registering aperture 27 and recess 26^d in the sheath and key, and the 100 notch 19, in the bar, in which position it is retained by a coiled spring 29, secured to the casing at 30 and engaging with one of its extremities, an upwardly ranging lug 28^d on the lower arm of the lever 28. The opposite arm 29^a of the spring 29, engages simultaneously, an upwardly extending projection or pin 20^a, on the long arm of the bell-crank 20, which, when the movable hook member is in the raised position, is, by reason of the engagement of the lower edge of the key with the extremity of its short arm, out of engagement with the 110 teeth of rack 18.

When it is desired to lock a hat, coat or other gar-

ment, suspended from the lower stationary hook-member 9, the operator depresses the raised, movable hook-member 10 until it engages the clothes, after which he removes the key from the sheath. During the downward movement of the slide 12, and the thereto attached bar 14, the extremity 28^a of the lever 28 is, by engagement with the sloping edge of the notch 19, gradually forced outwardly with the result that the opposite projection 28^a is carried out of the recess 26^a, of the key member 26. The action of the arm 29^a, of the coil spring 29, upon the lever 20, now causes the latter to engage the teeth of the rack and the slide 12 will, in consequence, be held at any elevation, the moment the pressure upon the hook 10 is released.

15 To unlock the device, the key is inserted in the sheath, to engage the upper extremity of the bell-crank 20, which on being depressed, is brought out of engagement with the rack, with the result that the slide 12, impelled by the contracting spring 17, moves upwardly 20 to resume its original position, as shown in Figs. 4 and 5, the engagement of the bent extremity 14^a with the lower surface of the seat 15, preventing further action of the spring. The lever 28, being once more in engagement with the notch 26^a, of the key member, locks 25 the latter against withdrawal, and simultaneously holds the bell-crank lever 20 out of engagement with the rack.

It will thus be observed that our improved rack may be employed with equal results, to lock several articles of clothing or any one of them, that to release these articles, one must possess the appropriate key, and that when the rack is not in use and the movable hook is in the raised position, the key is locked within its sheath.

Having thus described our invention what we claim is:—

35 1. The combination with a casing of a hook-member fixed thereon, a locking member having a linear, reciprocating movement in relation to the latter and extending

into the casing, its internal portion having a plurality of serrations, a key sheath extending into the casing, a key member adapted to project therethrough, a bell 40 crank lever, one of its arms extending below the sheath to be engaged by the protruding extremity of the key and its other arm being in yielding contact with the serrations, and an actuating medium adapted to distance the locking member from the hook member, when disengaged 45 by the bell crank lever.

2. The combination with a casing of a hook member fixed thereon, a locking member having a linear, reciprocating movement in relation to the latter and extending into the casing, its internal portion having a laterally 50 open notch, a key sheath having an aperture intermediate its extremities, a spring-actuated lever pivoted intermediate of its length and located between the key sheath and the locking member, its extremities projecting respectively through the said aperture and into the notch 55 when the locking member is remote from the hook member, a key member within the sheath having a notch normally in register with the aperture and means engaging the edge of the locking member for holding the locking member in its locked position, said means being controlled 60 by the key.

3. The combination with a casing having a key passage, of a hook-member fixed thereon, a locking-member having a linear, reciprocating movement relative to the latter and extending into the casing, its internal portion 65 having a plurality of serrations and a superposed notch, a notched key-member adapted to be inserted into the passage, a bell-crank lever normally in engagement with the said serrations and arranged to be engaged by the inserted key-member, a lever, its extremities respectively 70 engaging the notches in the key and the locking-member, while the latter is remote from the hook-member, a spring arranged to simultaneously actuate the two levers, and a spring tending to distance the locking-member from the hook-member.

In testimony whereof they have affixed their signatures in presence of two witnesses.

PHIL H. KNOWLTON.
LOUIS WILLIAMS.
